Oren Jordan

UNITED STATES PATENT OFFICE.

OREM JORDAN, OF FREEDOM, PENNSYLVANIA.

RAILWAY-SWITCH.

1,332,297.

Specification of Letters Patent.

Patented Mar. 2, 1920.

Application filed August 14, 1919. Serial No. 317,466.

To all whom it may concern:

Be it known that I, OREM JORDAN, a citizen of the United States, residing at Freedom, in the county of Beaver and State of Pennsylvania, have invented certain new and useful Improvements in Railway-Switches, of which the following is a specification.

My invention relates to new and useful improvements in railway switches, the primary object of which is to provide a means which will guide the movement of the train when passing through switches, thus preventing the splitting or picking of switch points, which frequently causes the derailment of trains.

A further object of my invention is to provide a means of the above mentioned character which will be actuated into and out of operative position by the movement of the switch lever.

A further object of my invention is to provide a means of the above mentioned character which may be attached to the switch of the ordinary structure without materially altering the same.

A further object of my invention is to provide a means of the above mentioned character which is simple in construction, easy to operate, reliable in such operation, and inexpensive to manufacture.

Other objects and advantages of this invention will be apparent during the course of the following description.

35 In the accompanying drawings forming a part of this specification and in which like numerals are employed to designate like parts throughout the same,

Figure 1, is a perspective plan view showing my improvement attached to a switch;

Fig. 2, is a transverse sectional view of my improvement, and

Fig. 3, is a perspective view of the base block with the guard member removed.

45 In the drawings, wherein for the purpose of illustration, I have shown a preferred embodiment of my invention, the numerals 5 and 6 designate the rails of the main track, while 7 and 8 designate the rails of a side track. The sectional portion 9 of the rail extends toward but terminates short of the rail 6, as does the rail 7 terminate short of the rail 5. Pivotally connected to the terminals of the rails 7 and 9 are switch pieces 10 and 11, which have their tips or

points arranged to engage the respective rails 5 and 6 in the usual manner. These rails are supported by the usual ties 12.

Arranged transversely of the track and connected to the underside of the switch 60 pieces 10 and 11 is a switch throwing bar 13. This bar has its free end bifurcated as at 14 to pivotally receive the hand lever 15 pivoted to the plate 15', as at 17. A plate 16 of a substantial rectangular shape having at 65 each end an up-turned lug 18 connected to the ends of the ties 12, as shown at 18', is provided with an inwardly projecting tongue 19, formed intermediate its ends.

A base block 20, placed between the rails 70 and extending longitudinally thereof is provided with flanges 21 which overlap the top of the ties and are secured thereto as shown at 22. This block is located in close relation to the jointure of the side track with 75 the main track. At the center and extending transversely of the block is a T-shaped recess 23, the head of which is adjacent the rail 6. The sides 24 of the stem of this recess are grooved as at 25, the said grooves 80 being curved upwardly. Slidably mounted within this recess is a guard member 26 of a shape similar to the recess. The outer edge of the guard member is arched in shape as shown at 27, the purpose of which is to 85 be described later. Projecting from the sides of the movable member are laterally extending pins 28 adapted to slide in the grooves 25, thus directing the transverse movement of the member 26. Adjacent the 90 forward end of the underside of the member 26 is a downwardly projecting lug 29, shaped to snugly fit within the opening 30 formed in the recess 23. The inner edge of the opening 30 is beveled as at 30', to facilitate the removal of the lug therefrom. The purpose of the lug is to normally prevent transverse movement of the member 26 when the switch is in an open position.

The bell crank lever 31 has a long and 100 short arm, the long arm being pivotally connected to the upper side of the tongue 19, midway its length, by the pivot pin 32. The free end of the long arm is provided with a link 33, which pivotally connects the lever 105 with the switch throwing bar 15 as shown at 34.

The rear end of the guard member 26 has projecting downwardly therefrom a U shaped staple 35 to receive the eyelet 36, 110

formed on one end of the reach rod 37. This reach rod extends transversely beneath the block 20 in a groove 38 provided for that purpose. The link 39 which connects 5 the reach rod and bell crank lever is bifurcated at one end to pivotally receive one end of the reach rod as shown at 40. The opposite end of the link is pivotally secured in the bifurcated portion 41 of the short arm of 10 the bell crank lever. Accordingly, the guard member 26 is connected to the switch lever 15 in such a manner that its actuating movement is governed thereby.

In operation when the switch is open, as 15 shown in Fig. 1, the guard member 26 is in a position so that the arcuate shaped end 27 is adjacent the main rail track 6. As is obvious, when a train approaches to enter the switch, the weight of the train is thrown 20 against the movable point 10, of the rail 7, which frequently causes the splitting or picking of the point, owing to the thinness of the point at its jointure with the main rail 5. In using my improvement this accident 25 is prevented, since the wheels on the opposite side of the train traveling on rail 6 will contact with the arcuate shaped end 27 of the guard member 26, thus holding the flanges of the wheels on track 5 out of contact 30 with the point 10, and at the same time divert the course of the train so that the train will pass through the switch without splitting or picking the points. To close the switch, the switch points 10 and 11 are oscillated by throwing the hand lever 15 backward, which in turn rocks the bell crank lever 31 through the medium of the link 33, thus exerting pressure upon the rod 37. The pressure on the rod 37 pulls the guard 35 member backward, which is elevated in its transverse movement by the pins 28 sliding in the curved grooves 25. When in this position, the guard member will not in any way interfere with the movement of the 40 train passing on the main track.

It is to be understood that the form of my invention herewith shown and described is to be taken as a preferred example of the same, and that certain changes in the shape, 50 size and arrangement of parts may be resorted to without departing from the spirit of the invention or the scope of the subjoined claims.

Having thus fully described my invention, 55 I claim:

1. In a switch, the combination of a main track, a siding, a base block, a guard member movable transversely on said block, a switch throwing mechanism, and means associated 60 with said guard member, whereby the same is actuated through movement of the switch.

2. In a switch, the combination of a main track, a siding, a base block between the track, a guard member movable transversely 65 on said block, one end being arcuate in

shape, a switch throwing mechanism, and means connecting the guard member to the switch throwing mechanism.

3. In a switch, the combination of a main track, a siding, a base block between the 70 track, a guard member movable transversely on said block, a switch throwing mechanism, a bell crank lever having one end associated therewith, and a rod extending beneath said base block connecting the guard member to 75 the opposite end of the bell crank lever.

4. A rail-point guard comprising a base block, a groove extending transversely across said block, and a guard member slideable in said groove to a position adjacent the rail-point.

5. A rail-point guard comprising a transversely grooved base block, a guard member slideable in said groove, means for retaining the member in a rigid position, and means 85 for actuating the guard.

6. In a switch, the combination of a main track, a siding, a transversely grooved base block, a guard movable in said groove, means for locking the member in an operative position, a switch throwing mechanism, and means joining the guard and switch mechanism.

7. In a switch, the combination of a main track, a siding, a transversely grooved base 95 block, slots in the sides of the groove, a guard member movable in the groove, pins extending from the sides of the guard for movement in said slots, a switch throwing mechanism, and means joining the guard 100 and switch mechanism whereby the same are operated simultaneously.

8. In a switch, the combination of a main track, a siding, a transversely grooved base block; a guard member slideable through the 105 groove, having means for guiding its movement, means for retaining the guard in an operative position, a switch mechanism, and means for joining the guard and switch mechanism whereby the same are operated 110 simultaneously.

9. In a switch, the combination of a main track, a siding, a base block, a T shaped groove extending across the block, a correspondingly shaped guard member slideable 115 in said groove, pins projecting from the member for movement in slots of the groove, means for retaining the member in an operative position, a switch mechanism, and a series of levers joining the guard with the 120 switch mechanism whereby the same are operated simultaneously.

10. In a switch, the combination of a main track having a siding associated therewith, a base block adjacent the jointure of the siding with the main track, a T shaped groove extending transversely across said block, a correspondingly shaped guard member movable in said groove, means for retaining said guard member in an operative position, a 125 130

switch mechanism, a rectangular plate extending longitudinally of the rails and secured to the supporting ties, a bell crank lever pivotally associated with said plate, a
5 reach rod extending beneath the base block having one end pivotally connected with the guard member and its opposite end pivotally connected with the bell crank lever, and means connecting the bell crank lever with

the switch mechanism whereby the same are 10 actuated simultaneously.

In testimony whereof, I have affixed my signature in the presence of two witnesses.

OREM JORDAN.
